UNITED STATES PATENT OFFICE.

CLARENCE H. COREY, OF MURDO, SOUTH DAKOTA.

GATE.

Application filed March 11, 1926. Serial No. 93,972.

The present invention relates to improvements in gates, and has for its principal object to provide one which is adapted for both swinging and sliding movement.

5 One of the important objects of the present invention is to provide a gate of the above mentioned character wherein the same is supported on a vertical pivot, the gate being further adapted for horizontal 10 translation so as to disengage the free end of the gate from the vertical post or standard and permit the swinging movement of the gate on its vertical pivot.

A still further object is to provide a gate 15 of the above mentioned character wherein means is provided for preventing the sagging of the free end of the gate so that the same is at all times kept out of engagement with the ground during the swinging movement of the gate.

A still further object is to provide a gate 20 of the above mentioned character which is simple in construction, inexpensive, strong and durable and further well adapted to the purpose for which it is designed.

Other objects and advantages of the invention will become apparent during the course of the following description taken in connection with the accompanying drawings.

In the accompanying drawing forming a part of this application, and in which like numerals designate like parts throughout the same:

35 Figure 1 is a side elevation of the gate showing the same in its normally closed position.

Figure 2 is a similar view showing the gate after the same has been slid laterally so 40 that the free end of the gate is disengaged from the vertical post.

Figure 3 is an elevational view showing the position of the gate when the same has been swung to its open position.

45 Figure 4 is a vertical sectional view taken approximately on line 4—4 of Figure 1 looking in the direction of the arrows.

Figure 5 is a detail perspective view of the arm forming a part of the present invention, and

50 Figure 6 is a detail perspective view of the auxiliary frame which is associated with the gate.

In the drawings, wherein for the purpose 55 of illustration is shown the preferred em-

bodiment of my invention, the numeral 1 designates generally the gate, the same comprising the substantially rectangular shaped frame 2, which is formed preferably of tubular steel. Vertically arranged braces 3 60 extend between the upper and lower portions of the frame in the intermediate portion of the gate as clearly shown in the drawing, and a series of wire rods indicated at 4, are associated with the frame in any 65 suitable manner.

Adapted to be associated with the gate 1 is what I term as an auxiliary frame indicated at 5, the same being also formed of tubular steel. The auxiliary frame 5 has its 70 intermediate portion 6 disposed vertically and secured to the rear end portion of the main frame 2 of the gate 1 in spaced relation thereto through the medium of the clamping members 7. The end portions of 75 the auxiliary frame are disposed laterally or horizontally as indicated at 8 and 9 respectively, the portion 8 being of greater length than the end portion 9.

The end portion 9 is adapted to extend adjacent the upper horizontal portion of the main frame 2 of the gate 1 adjacent the rear end thereof, and is secured at its free end thereto by the clamp 10 in such a manner as to space the end portion 9 from the upper 80 portion of the main frame. The longer end portion 8 of the auxiliary frame 5 extends longitudinally across the gate 1 adjacent the bottom thereof, and the free end of the lower portion 8 of the auxiliary frame is disposed 85 downwardly as illustrated at 11 with reference more particularly to Figure 6, and this free end portion 11 is secured to the forwardmost vertical brace 3 by means of a suitable clamp 12. The provision of the 90 clamping members enables the auxiliary frame to be maintained in parallel spaced relation with respect to the rear side of the gate 1 and the purpose of spacing the auxiliary frame with respect to the main frame 95 of the gate will be readily apparent from the following description.

Adapted for slidable movement on the auxiliary frame 5 is the arm carrying member 13. This member is formed of an elongated flat strip of metal which is bent intermediate its ends to provide a looped portion and a pair of parallel spaced strips 15 and 16 respectively, as is more clearly shown in Figure 4. The portion 14 of this member 100 105 110

is slidable over the upper portion 9 of the auxiliary frame 5, while the lower free ends of the spaced strips 15 and 16 are adapted to be disposed over the other end portion 8, 5 the strip 15 being disposed between the main frame and the auxiliary frame.

A roller such as is shown at 17 is supported between the strips 15 and 16 adjacent the looped portion 14 on which the end portion 19 of the auxiliary frame is adapted to travel during the sliding movement of the gate as will be hereinafter more fully described. A similar roller 18 is also supported between the strips 15 and 16 of the arm carrying member 13 at a point adjacent the lower free end thereof, and the other end portion 18 of the auxiliary frame travels thereover.

This arm carrying member 13 further provides a means for pivotally supporting the gate on the vertical post 19 which is arranged adjacent one side of the road or entrance, and to this end, there is provided on the outer face of the strip 16 the laterally extending apertured ears 20 which are disposed over the upstanding portion 21 of the pivot pin 22 which extends laterally from the post 19 as is clearly shown in the several views on the drawing. This construction provides a means whereby the rear end of the gate 1 is pivotally supported on the post 19, the free end of the gate being adapted for cooperation with the vertical post 23 which is disposed on the opposite side of the road.

35 An arm 24 is formed of an elongated strip of metal, is folded or bent along its longitudinal center to provide the upstanding parallel spaced sides 25 and 26 respectively has its rear end bifurcated and the bifurcations formed by such construction are pivotally secured on opposite sides of the strips 15 and 16 of the arm carrying member 13 at a point adjacent the lower ends of said strips as indicated at 27. The arm 24 encloses a portion of the end portion 8 of the auxiliary frame 5, and this end portion is further adapted for slidable movement through the arm 25 between the spaced upstanding sides 25 and 26 thereof, and as is clearly shown in the drawings, a roller 28 is supported in the forward end of the arm, and cooperates with the roller 18 in holding the bottom of the arm out of engagement with the end portion 8.

55 The forward ends of the sides 25 and 26 are reduced and disposed upwardly as indicated at 29 and 30 respectively, and the outer ends are provided with registering openings for accommodating one end of a relatively short chain 31. The upwardly disposed portions 29 and 30 are further curved outwardly so as to free end portion 8 of the auxiliary frame. The other end of the chain 31 is adapted for detachable engagement with the hook 32 formed on one end of the rod 33, the

latter having attached to its rear end a contractile coil spring 34 which in turn is secured to a hook 35. This hook 35 is provided with an eye portion at its rear end, and the eye portion is mounted on a transversely extending pin 36 which extends through the strips 15 and 16 of the arm carrying member 13 at a point adjacent the looped upper end thereof as clearly shown in Figures 3 and 4 of the drawings.

The connection between the forward end of the arm 24 and the upper portion of the arm carrying member 13 as just described provides a means for preventing the sagging of the forward free end of the gate as well as tending to hold the forward end of the gate upwardly during the swinging movement of the gate to an open position so that the lower forward portion of the gate will not come in contact with the ground, and thereby the gate will be permitted to swing freely and easily.

With the parts arranged as shown in Figure 1 of the drawing, the gate 1 is maintained in a closed position, and the same cannot swing forwardly to an open position due to the fact that the free end of the gate is disposed behind the post 23. Furthermore, the gate cannot swing rearwardly, due to the arrangement of the arm carrying member and the auxiliary frame 5. In order that the gate may be swung to an open position, it is necessary that the rear end of the gate be moved horizontally, and this is accomplished by sliding the end portions 8 and 9 of the auxiliary frame 5 rearwardly and through the arm carrying member, and the arm 24 along the rollers 17, 18, and 28 so that the forward free end of the gate will be disengaged from the post 23, and when the gate 1 is in the position shown in Figure 2, the spring 34 will cooperate with the free end of the arm 24 in raising the forward end of the gate upwardly.

The gate 1 is then free to swing on the vertical pivot 21 in a forward direction so that the gate will be disposed parallel with the side of the road adjacent the post 19 in the position as shown more clearly in Figure 3 of the drawings.

It will thus be seen from the foregoing description that I have provided a highly novel gate which is adapted for both pivotal and slidable movement, the parts being so arranged as to enable the same to be readily and easily operated, and being furthermore at all times positive and efficient in their operation.

While I have shown the preferred embodiment of the invention, it is to be understood that there may be such minor changes made in the size, shape, and arrangement of parts without departing from the spirit of the invention, and the scope of the appended claims.

Having thus described the invention, what I claim as new and desire to secure by Letters Patent is:—

1. In combination with a pair of opposed posts, a gate including a main frame, and an auxiliary frame arranged in spaced relation with respect to the main frame at one end thereof, and means affording a pivotal connection between the rear end of the gate and one of said posts whereby the gate may be swung on a vertical pivot, said means further cooperating with the auxiliary frame to permit horizontal translation of the gate whereby the free end of the gate is moved out of engagement with the opposed post to permit the free swinging movement of the gate.
2. In combination with a pair of opposed posts, a gate including a main frame, and an auxiliary frame arranged in spaced relation with respect to the main frame, at one end thereof, and means affording a pivotal connection between the rear end of the gate and one of said posts whereby the gate may be swung on a vertical pivot, said means further cooperating with the auxiliary frame to permit horizontal translation of the gate whereby the free end of the gate is moved out of engagement with the opposed post to permit the free swinging movement of the gate.

one end thereof, and means affording a pivotal connection between the rear end of the gate and one of said posts whereby the gate may be swung on a vertical pivot, said means further cooperating with the auxiliary frame to permit horizontal translation of the gate whereby the free end of the gate is moved out of engagement with the opposed post to permit the free swinging movement of the gate, said means comprising a member disposed over the upper and lower portions of the auxiliary frame and through which member said portions of the auxiliary frame are adapted to slide, laterally extending apertured ears carried by said member, and pivot pins carried by the first mentioned post and extending through the apertured ears.

In testimony whereof I affix my signature.

CLARENCE H. COREY.
